Attorney

UNITED STATES PATENT OFFICE.

E BLAKE SHAND, OF DETROIT, MICHIGAN.

VENTILATING WINDOW-HINGE.

1,365,063.

Specification of Letters Patent. Patented Jan. 11, 1921.

Application filed January 15, 1919. Serial No. 271,188.

To all whom it may concern:

Be it known that I, E BLAKE SHAND, citizen of the United States, residing at Detroit, county of Wayne, State of Michigan, have invented a certain new and useful Improvement in Ventilating Window-Hinges, and declare the following to be a full, clear, and exact description of the same, such as will enable others skilled in the art 10 to which it pertains to make and use the same, reference being had to the accompanying drawings, which form a part of this specification.

My invention relates to a window ventilating hinge shown in the accompanying drawings and more particularly described in the following specification and claim.

Primarily the object of my invention is to provide a device whereby the upper or lower 20 sash of a slidable window may be swung inwardly for purpose of ventilation;—or when it is desired to clean the window.

With the foregoing and other objects in view which will appear as the description 25 proceeds, the invention resides in the combination and arrangement of parts and in the details of construction hereinafter described and claimed, it being understood that changes may be made in the precise embodiment of the invention herein described without departing from the spirit of the same.

In the drawings forming part of this specification:—

Figure 1 is a fragmentary vertical sectional view through the lower portion of a window sash and its supporting casing;—showing the sash in a vertical position with the cup-shaped member of the hinge lodged in a mortise formed in the side frame of the 40 sash,—showing also the co-acting member of the hinge attached to the wall of the window jamb.

Fig. 2 is a similar sectional view, the inner stop and also the parting stop being first 45 removed;—showing the upper and lower sash swung to a horizontal position and resting upon the window stool in position for cleaning.

Fig. 3 is a fragmentary perspective view 50 of a window casing, showing one member of the hinge secured to the jamb.

Fig. 4 is a fragmentary perspective view 55 of a window sash showing the other member of the hinge secured in a mortise formed in the sash frame, also indicating a frag-

ment of the sash supporting ribbon, in turn secured to the usual sash cord.

Fig. 5 is a vertical sectional view through the sash frame and window jamb on line 5—5 of Fig. 1.

Referring now to the letters of reference placed upon the drawings:—

A, denotes a window frame. B, the window jamb. C, indicates the inner detachable stop. D, the parting stop, a portion 65 D¹ of which is removable. D² is a spring secured to the end of the removable section adapted to bear against the abutting end of the fixed portion of the parting stop to force the lower dovetailed end D³, of the removable section into contact with lower fixed portion of the parting stop, as shown in Fig. 3.

Respectively secured to the window jamb and lodged in a mortise formed in the side 75 frame of the window sash are members which coöperate to form a hinge whereby the sash may be tilted at an angle to its usual vertical position in order to provide for ventilation, or the sash may be swung 70 into a substantially horizontal position for cleaning the glass.

In carrying this into effect, E, denotes a projecting stud (constituting one member 85 of the hinge) which is preferably elliptical in form and constructed of sheet metal with an aperture to receive a screw F, whereby the stud may be secured to the jamb. E¹ are projecting points adapted to enter the wood to prevent the stud turning upon the 90 shank of the screw.

G, is a cup-shaped element (constituting the coöperating member of the hinge) provided with a channel G¹, opening into the cup-shaped portion of the member. The element G is lodged in a mortise cut in the edge of the side members of the sash frame and is secured therein by a screw H, extending into the wall of the sash. The open channel portions of the cup-shaped elements 100 of the upper and lower sashes are offset forwardly from the centers of the said cup-shaped elements, and the studs E which co-operate with the cup-shaped elements are offset forwardly from the centers of the 105 guideways of the window frame or casing, and are in position to pass through the channels of the cup-shaped elements when the sashes are in a vertical position. These studs E which are of a size to lie off center 110

of the cup-shaped elements, when the sashes are swung downwardly to a horizontal position, are adapted by means of the sidewise play of the cup-shaped elements over them 5 to permit the lower sash to rest flat upon the bottom of the window frame or casing and the upper sash to rest upon the lower sash as illustrated in Fig. 2 of the drawings.

I, designates a metallic ribbon pivoted at 10 I¹, to the edge of the sash and secured at its upper end to the usual sash cord J.

Having indicated the several parts by reference letters, the construction and operation of the device will be readily understood:—When it is desired to tilt the lower sash for purposes of ventilation, the inner stop C, is first removed and the sash swung inwardly and secured by a suitable fastening device, forming the subject matter of 15 another patent. If the windows are to be washed, the sash is swung down to a horizontal position so as to rest upon window stool;—the upper sash may also be lowered and swung into a horizontal position so as to 20 rest upon the lower sash, upon first withdrawing the removable portion of the partition stop, D¹, as shown in Fig. 2 of the drawings.

The removable portion, of the stop D, is 25 held in place by the pressure of the spring D², forcing said removable section against the end of the lower section, when the sash is in its usual position, as has been previously explained.

It will be noted that the length of the stud E, is greater than the width of the channel G¹ leading into the cup-shaped ele- 30

ment and while it is adapted to freely enter the cup-shaped element when the sash is moved vertically, it forms a secure pivot 40 for the sash upon the latter being tilted due to the length of the stud being greater than the width of the channel portion of the co-acting cup-shaped element.

Having thus described my invention, what 45 I claim is:—

In a device of the character described the combination with a window frame or casing and upper and lower sashes of cup-shaped elements embedded in the sashes and each having an open channel portion leading to the interior of the said cup-shaped element and offset forwardly from the center thereof, and cooperating studs secured to the window frame and offset forwardly from the centers of the guideways thereof and adapted to enter the said cup-shaped elements by way of the channel portions when the sashes are in a vertical position and being of a size to lie off center of said cup-shaped elements when the sashes are swung downwardly to a horizontal position to provide for sidewise play of the cup-shaped elements over the studs to permit the lower sash when in the said horizontal position to drop and 55 rest on the bottom of the window frame or casing and the upper sash to rest upon the lower sash.

In testimony whereof, I sign this specification in the presence of two witnesses.

E BLAKE SHAND.
